UNITED STATES PATENT OFFICE

LOUIS WILLBORG, OF NEW YORK, N. Y., ASSIGNOR TO R. HOE & CO., INC., OF NEW YORK, N. Y., A CORPORATION OF NEW YORK

MOLD FOR CASTING STEREOTYPE PRINTING PLATES

Application filed November 18, 1929. Serial No. 407,964.

This invention relates to molds for casting stereotype plates and especially flat stereotype plates.

Molds of this class are arranged to be turned to a horizontal position so they may be opened and the matrix placed therein in proper position, after which the mold is closed and turned to a vertical position for casting the plate. The thickness of flat stereotype plates is determined by the manner in which they are to be used, and it is desirable to arrange the mold so that it can be adjusted to cast a plate of any thickness desired. This arrangement has been met in the mold disclosed herein by a novel mechanism.

An object of the invention is to provide a device for casting flat stereotype plates in which the cover member of the mold is hinged to the bottom member and the separation between the cover and bottom members may be adjusted to suit the thickness of the plate that it is desired to cast.

It is also an object of the invention to provide a device for casting flat stereotype plates that is of generally improved construction, whereby it will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

Certain features of the casting mold shown in the accompanying drawings and not claimed herein are claimed in the co-pending application of William F. Huck, Serial No. 407,952 filed November 18, 1929.

The preferred embodiment of the invention is illustrated in the accompanying drawings, wherein:

Figure 1 shows a side view of the complete casting device except that certain portions of the side frame, forming no part of the invention, are broken away; and

Figure 2 is a sectional view showing the mold as viewed on the line 2—2 on Figure 1 and in the direction of the arrow.

Referring to the drawings, 11 indicates one of the side frames, of which there are two, 55 adapted to support the mold, and which are held in proper spaced relation by suitable cross members 12, 13 and 14. The mold includes a bottom member 15 and a cover member 16. Side bars 17 and 17', are secured 60 to cross members 19 and 19' which pass through slots 21 and 21' formed in the bottom member 15, and thus form a support for the bottom member 15. Hand screws 22, are threaded into the cross members 19 and 19' 65 and bear against sockets 23, formed in the bottom member 15 of the mold, thus providing means for adjusting the bottom member relatively to the cross members 19 and 19'. Side bars 17 and 17' are extended to form a 70 support for a shaft 24, to which they are secured and which passes through a portion of the cover member 16, thus providing a hinge connection between the cover member and the side bars. Trunnions on which the mold may be swung, are formed by studs 26, secured to the side bars 17 and 17'. Rollers 27, are rotatably secured to the studs 26, and adapted to run on horizontal finished ways 28, on the frames 11. Guide ways 29, are formed in the 75 side frames and are engaged by a shaft or follower 30, that is secured to arms 31, formed on the side bars 17 and 17'.

Cams 32, are secured to a shaft 33, that turns in bearings formed in the cover member 16 and are adapted to engage studs 34, secured to the side bars 17 and 17'. An arm 35, is secured to the shaft 33 and provides a convenient means for locking and unlocking the cams. A means for locking the mold to 80 prevent it from being moved from the position shown in Figure 1, is provided by a hook 43, which is pivoted on a stud 44, secured to the side frame 11. The hook 43, is provided with a handle 45, for manual operation and acts to hold the mold in the position shown in Figure 1.

Side gages 51, and a bottom gage 52, form the sides and foot of the casting chamber. These gages may be of variable height de-

70 pending on the thickness of the plate that it is desired to cast. Adjustment to provide for this variable thickness may be made by screws 22, and it will be readily understood that when gages of lesser height are used, the screws 22, may be screwed in, and thus raise the bottom member of the mold closer to the cover. The movement of the bottom member relative to the side bars is permitted by the 75 slots 21 and 21'.

75 A spring 54, is provided to counteract the weight of the cover, one end of the spring being secured to the cover by means of the bolt 55, and the other end being secured to the bottom member of the mold by means of the stud 56, and the nut 57. A handle 58, provides means for raising or lowering the cover and moving the complete mold when the two members are locked together.

80 85 In operation, starting with the mold in the horizontal position as shown in Figure 1, the cover is raised by turning it on the shaft 24, in order to open the mold to adjust the matrix and the side gages in proper position. It is then closed and the two members locked together by operation of the handle 35. The hook 43, is released by the operation of the handle 45, and the mold is then moved forward on the rollers 27, and along the ways, and simultaneously turned about the axis of the rollers, by the follower 30 acting on the 90 guide 29. This results in bringing the mold to a vertical position at the left hand side of the frame, ready for casting the plate. After 100 the plate is cast, the mold may be moved back to the original position and the plate removed.

95 From the foregoing description, it will be understood that a mold has been provided that can be conveniently operated to adjust the matrix and cast the plate, and that can be adjusted to adapt it for use in casting plates of any thickness within the limits required.

110 115 What I claim is:

1. In a mold for casting flat stereotype plates, a bottom mold member, a cover mold member, and a support hinged to one of the mold members and adjustably secured to the 120 other mold member; said support being arranged to permit swinging the mold from a substantially horizontal to a substantially vertical position.

2. In a mold for casting flat stereotype plates, a bottom mold member, a cover mold member, a support hinged to the cover member, and means for adjustably securing the bottom member to the support; said support being arranged to permit swinging the mold 125 from a substantially horizontal to a substantially vertical position.

3. In a mold for casting flat stereotype plates, a bottom mold member, a cover mold member, a support to which the cover member is fastened, and adjustable means for se-

curing the bottom member to the support; said support being arranged to permit swinging the mold from a substantially horizontal to a substantially vertical position.

4. In a mold for casting stereotype plates, a bottom mold member, a cover mold member, a support to which the cover member may be locked, and means to secure the bottom member to the support, whereby the space between the bottom member and the cover member may be varied; said support being arranged to permit swinging the mold from a substantially horizontal to a substantially vertical position.

5. In a mold for casting flat stereotype plates, a bottom mold member, a cover mold member, a support hinged to one of the mold members and secured to the other mold member, and means for adjusting the position of the said other mold member with respect to the support, whereby the space between the bottom member and the cover member may be varied; said support being arranged to permit swinging the mold from a substantially horizontal to a substantially vertical position.

6. In a mold for casting stereotype plates, a bottom mold member, a cover mold member, and means hinged to the top member and adjustably secured to the bottom member, whereby the top member may be swung to open and close the mold and the space between the cover member and the bottom member may be varied for casting plates different in relative thickness; said means being arranged to permit swinging the mold from a substantially horizontal to a substantially vertical position.

In testimony whereof, I affix my signature.

LOUIS WILLBORG.
